UNITED STATES PATENT OFFICE.

GEORGE N. CRAWFORD, OF CHICAGO, ILLINOIS, ASSIGNOR TO LIDGERWOOD MANUFACTURING COMPANY, OF NEW YORK, N. Y., A CORPORATION OF NEW YORK.

TURN-TABLE.

1,031,425.

Specification of Letters Patent. Patented July 2, 1912.

Application filed May 6, 1909. Serial No. 494,432.

To all whom it may concern:

Be it known that I, GEORGE N. CRAWFORD, a citizen of the United States, and a resident of Chicago, in the county of Cook and State of Illinois, have invented certain new and useful Improvements in Turn-Tables, of which the following is a specification.

The use of turn-tables is common in connection with many types of machines bearing derricks and the like which it is desired to operate at different points around the machine, the base of the machine remaining in a fixed position and only the upper portion or that bearing the derrick, etc., being adapted to turn. Moreover, such a use of turn-table is very commonly made in connection with machines adapted to operate and movable on a track, it being desired to operate the derrick or the like carried by the machine from any desired point on either side or end and the engine, boiler, etc., for generating the power to operate the machine generally being carried on the turn-table.

It is the purpose of my invention to provide a turn-table of simple and comparatively light construction which may be turned readily with a minimum of power required, the construction being such as to avoid friction between moving parts and obviate any danger of difficulty in turning the table through jamming or the like. Furthermore, I have provided a novel construction and arrangement of mechanism for turning the table.

In the drawings herewith I have shown and will hereafter describe my invention as embodied in the turn-table of an excavating machine adapted to operate upon a track but it will be obvious that various and desired uses of my invention may be made without departing from the spirit of the invention which consists in the design, arrangement, combination and operation of parts as set forth in and falling within the scope of the claims hereto appended.

In the drawings herewith like characters of reference denote like parts in all the figures thereof; Figure 1 represents a side view in elevation of an excavating machine provided with a turn-table embodying my invention; Fig. 2 represents a plan view of a turn-table embodying my invention, the top section or floor portion of the turn-

table bearing the floor of the excavating machine being removed; Fig. 3 represents an end view in elevation of a turn table embodying my invention a portion of the end being broken away to show concealed parts; Fig. 4 represents a sectional end view in elevation taken centrally across a turntable embodying my invention.

In the excavating machine shown for the purpose of illustration, the engine A boiler B and derrick C are carried on the floor portion D of the turntable. To the floor portion D underneath the same is secured a rail circle 1 resting upon wheels 2 preferably tapered, which in turn rest upon a rail circle 3 mounted on the stationary base 4, which latter is provided in this instance with wheels 6 resting upon a track 7. In the portion D of the turntable centrally of the rail circle 1 is mounted a casting 8 extending downward and entering a casting 9 carried by the base 4 and positioned centrally of the rail circle 3 on said base. The casting 9 is provided with a circular shoulder 10 upon which rests a circular plate 11; from the plate 11 radiate the arms 12 of a spider, each arm having mounted thereon adjacent its end a tapered wheel 2 and the ends of the arms 12 being united by a restraining ring 13. From the above description it will be seen that the rail circle 1 secured underneath the floor portion of the turntable, rests and is free to turn upon the wheels 2, while the wheels 2 carried by the spider rest and are free to move on the rail circle 3 on the base of the turntable. The turning of the floor portion of the turntable about the axis of its rail circle 1 is independent of any turning of the spider-bearing wheels 2 about its axis and vice versa; in this manner the friction between moving parts upon the rotation of the turntable is reduced to a minimum. In the preferred form of construction the turning power is applied directly to the floor portion of the turntable which then rotates or turns on wheels 2, the latter moving on the rail circle on the base, the turning of the wheel spider being at a slower rate of speed than that of the floor portion. The turn-table so constructed may be readily and rapidly set in motion with little power and its movement easily controlled or checked.

For the purpose of securing the rotation-

of the turn-table I have provided a novel form of construction adapted in the preferred form of construction to be operated by an engine mounted on the turn-table itself. A circular toothed rack 14 is mounted on supports 15 extending upward from the base 4, the rack being greater in diameter than the rail circles and wheel spider, and provided with outwardly projecting teeth 16. Mounted in the floor of the turn-table and extending downward through the same outside of the rail circles and wheel spider are castings 17 and 18 which form bearings for vertical shafts 19 extending through the same. Each shaft 19 is provided at its lower end with a gear pinion 20, the pinions 20 being in a horizontal plane with rack 14. An endless chain 21 passes around the pinions 20, its inner length meshing on its outer portion with the teeth of rack 14 and being pressed outward to conform to the curve of the rack sufficiently to secure an engagement between the chain and a plurality of the teeth of the rack. Shaft 19 passing through bearing 17 extends above the bearing and is provided at its top with a bevel gear 22 engaging with a pinion 23 on shaft 24, which is driven from an engine on the turntable. In order to maintain a tension on the chain 21 to keep the same stretched tightly between the pinions 20, and in secure engagement with the rack, casting 18 passes through an enlarged aperture in the under flooring of the turn-table and is provided with a plate 25 resting against the under side of the upper flooring of the table and a second plate 25 resting on the under flooring around the aperture or opening therein. Thus, casting 18 is capable of movement laterally away from or toward casting 17, and a tension spring 26 is provided secured to the turn-table and to casting 18 which tends to pull the latter away from the casting 17 and thus maintains a tension on the chain 21 to keep the same stretched tightly between the pinions 20. Movement of the turn-table is readily secured by the operation of shaft 24 to move the chain 21, the direction of rotation of the turn-table being in a direction opposite to the movement of the chain at its point of engagement with rack 14. The chain 21 is always stretched tightly between the pinions around which it passes and is held in firm engagement with the rack, at the same time being capable of yielding to any unusual strain or shock without breaking.

A turn-table embodying my invention is particularly efficient because of the ease and simplicity with which it may be turned and its movement controlled.

Having thus described my invention, what I claim as new and desire to secure by Letters Patent is as follows:

65 1. A turn-table comprising a stationary

base, a floor portion and means for turning the floor portion, said means comprising a circular toothed rack fixedly mounted on the base, an endless chain carried by the floor portion and meshing with the outer face of one of its runs with said rack, and means on the turn table for operating the chain. 70

2. A turn-table comprising a stationary base, a floor portion and means for turning the floor portion, said means comprising a circular toothed rack fixedly mounted on the base, two vertical shafts extending downward from the floor portion, a pinion at the lower end of each shaft, an endless chain passing around said pinions and meshing at 80 the outer face of one of its runs with the rack, and means on the turn table for operating one of said shafts. 75

3. A turn-table comprising a stationary base, a floor portion, and means for turning the floor portion, said means comprising a circular toothed rack fixedly mounted on the base, a stationary pinion and a movable pinion mounted on the floor portion and movable therewith, an endless chain passing 90 around said pinions and meshing at the outer face of one of its runs with said rack, a tension member connected to said movable pinion and means on the turn table for operating one of said pinions. 95

4. A turn-table comprising a floor portion, hoisting apparatus thereon, a base mounted upon running wheels, a hoisting engine mounted upon said floor portion for operating the hoisting apparatus, and including 100 a horizontal power shaft, and means for turning the table comprising a rack on the base, a pair of vertical shafts on the floor portion, a sprocket chain running over sprockets on said shafts and engaging said rack, with the outer face of one of its runs, a horizontally disposed shaft geared to the said power shaft and to one of said vertical shafts whereby the hoisting engine may be operated to drive the turn-table. 105

5. A turn-table comprising a floor portion, a base upon which said floor portion is rotatably mounted, means for driving the floor portion comprising a rack mounted on the base, vertical shafts carrying sprockets supported by the floor portion, one of said shafts being mounted in a cushioned bearing to permit it to move toward the other shaft, a sprocket chain running over the sprockets on said shafts and meshing at the 115 outer face of one of its runs with said rack, and means for driving one of the shafts. 120

6. A turn-table comprising a floor portion, a base upon which said floor portion is rotatably mounted, means for driving the floor portion comprising a rack mounted on the base, vertical shafts carrying sprockets supported by the floor portion and moving therewith, one of said shafts being slideable 125 toward and away from the other shaft, a 130

tension device to permit said slidable shaft to slide toward the other shaft, a sprocket chain running over the sprockets on said shafts and meshing at the outer face of one of its runs with said rack, and means for driving the chain.

5 In testimony whereof I have signed my

name to this specification in the presence of two subscribing witnesses.
